UNITED STATES PATENT OFFICE.

WILLIAM H. SAUNDERS, OF NEW LONDON, CONNECTICUT.

TIMING AND IGNITION DEVICE.

942,936.

Specification of Letters Patent. Patented Dec. 14, 1909.

Application filed August 31, 1908. Serial No. 451,073.

To all whom it may concern:

Be it known that I, WILLIAM H. SAUNDERS, a citizen of the United States of America, residing at New London, in the county of New London and State of Connecticut, have invented new and useful Improvements in Timing and Ignition Devices, of which the following is a specification.

10 My invention relates to improvements in spark and timing devices for internal combustion engines in which a make and break contact mechanism is operated by a pair of levers which are so arranged as to pass by one another and at the end of their travel to effect a quick action of the make and break device.

The objects of my improvements are, 1st: To provide means for varying at will the 20 time of operation of the spark mechanism whereby the charge in the engine cylinder may be exploded either earlier or later in the rotation of the crank-shaft and thus cause the engine to rotate in opposite directions, if desired; 2d: To provide means for effecting a very sudden or quick action of the make and break device; 3d: To provide means for placing the make and break contact device under tension whereby fouling or 30 sooting of the contact device may be prevented; 4th: To provide means for connecting the same to some rotating part of the engine.

Other objects of the improvement will 35 appear in the body of the specification and be particularly pointed out in the claims.

The invention is designed primarily to be used in connection with marine engines in the operation of which it is often desirable to reverse the direction of rotation for the purpose of propelling the boat, either ahead or astern, as may be desired, and I have devised a sparking and timing device whereby this result may be successfully accomplished as will be fully described.

In the drawings forming part of this application, Figure 1 represents an assembled plan view of the device showing the contact levers in mid position. Fig. 2 is a detail plan view showing the contact levers just before they separate to produce the spark in the engine cylinder. Fig. 3 is a partial sectional view showing the interior arrangement of the make and break device and in 55 side elevation the connecting means between the rotating crank disk and the cross-head to

which one of the contact operating levers is connected. Fig. 4 is a partial sectional view taken on the line 4—4 of Fig. 3 clearly showing the means for varying the timing 60 action of the make and break device, and the operating lever in plan view. Fig. 5 is a detail plan view of the operating contact levers of a modified form, and Fig. 6 is a detail sectional view on line 6—6, Fig. 5, 65 showing clearly the construction of the insulated joint. Fig. 7 is a detail view of the lever connection between the main shaft and the adjusting lever.

Referring to the drawings in detail, in 70 which like characters indicate the same element, *a* designates the engine cylinder as a whole, and *b* a plate secured thereto for supporting the spark-plug *c*, make and break contact arm *d*, and the operating parts as- 75 associated therewith.

e designates a shaft extending through the plate *b* and the block or hub portion *f* which is made integral therewith and which fits 80 into an opening *g* in the cylinder wall. 80

h designates the securing means for the plate *b* and block *f* for attaching the same to the engine cylinder.

i is a stud mounted on the plate *a* to which is secured one end of a coil spring *j*, its 85 other end being attached to an arm which is attached to the shaft *e* whereby the contact arm *d* is normally held in contact with the inner end of the spark-plug *c*, as shown in Fig. 3. The spark-plug *c* of the plug passes 90 through conical shaped bushing pieces *k* which leave a space *c*² between the shank *c*¹ and the opening *c*³ in the block *f*, as shown in Fig. 3.

95 Mounted on the shaft *e* is a double-armed spring-supporting U-shaped member *m* and in the outer end of said arms are located compression springs *o* and *p* that act in opposite directions on a contact opening and closing arm *q* which is rotatably mounted on 100 the shoulder *m*¹ of the member *m*, which member is fixedly secured to the shaft *e* on which is mounted a make and break contact finger *d*. The outer end of the contact-closing arm *q* is provided with an integral 105 elliptical boss or lug *r* that extends at right angles to the plane of the contact-closing arm *q*. Operatively located with relation to the arm *q* is a second arm *s* that is pivotally mounted on a cross-head or sliding member *t* at *s*¹ and is adapted to be moved back and forth on the slide *u*. The sliding 110

member *t* is provided with a lug *v* and a stop *w* that is threaded therethrough and adapted to be locked in various adjusting positions by means of the nut *x*. This stop *w* is for the purpose of adjusting the free end of the member *s* with relation to the member *q* which is also provided with an elliptical shaped lug *y* that extends in a plane at right angles to the arm *s*. A spring *z* is interposed between the arm *s* and a lug *2* of the cross-head *t*, which spring serves the purpose of holding the arm *s* constantly against the stop *w*. Further reference will be made to the movements of the two arms *s* and *q* in describing the operation of the machine.

3 designates a bracket that is made integral with the engine cylinder, or if desired it may be made separate and suitably secured thereto. In the outer end of this bracket is mounted a shaft *4* that is adapted to be driven from some rotating member of the explosion engine.

5 designates a bearing-block that is mounted in the upper end of the bracket 3. This block is adapted for rotation in the bracket by reason of the spiral groove 6 that is cut therein, a pin or stud 7 engaging this groove. An arm 8 extends from the bracket 3, in the outer end of which is pivotally mounted a lever 9. On this lever is mounted a spring-pressed detent 10 that is adapted to lock the lever 9 in various positions of adjustment on the sector-shaped arm 11. The forward end of the spring detent 10 is wedge-shaped for entering the teeth 12.

The lever 9 is adapted to impart rotary movement to the bearing block 5 by means of the bearing element or sleeve 13 that extends outward from the block 5 toward the lever 9. The lever 9 is provided with a yoke 14 in which are mounted the pins 15 which extend inward toward the shaft 4 and engage blocks 16, which are mounted in the groove 17 of the collar 18. This collar is made integral with the bearing element or sleeve 13 and the pin 7 (referred to above) is carried in the outer end of the bearing element 13 so that when the lever 9 is moved forward or backward the bearing element 13, through the pin 7, will rotate the bearing block 5 and consequently change the relation of the stroke of the connecting-rod 19, one end of which is pivotally connected to a plate 20 that is secured to the bearing-block 5, and the other end of which is pivotally connected to the sliding member *t*, at the point 21.

A spline and groove connection is shown in dotted lines in Fig. 4 between the shaft 4 and the element 13 whereby rotary movement is imparted from the shaft 4 to the sleeve 13, and whereby, by means of the pin 7, which is carried in the outer end of the sleeve 13, rotary movement is imparted to

the bearing-block 5 and to the disk-member 20 which is secured to the bearing-block 5, by means of the screw 22. The disk member 20 therefore imparts reciprocating motion to the slide *t* through the connecting rod 19, as above mentioned.

Referring to Fig. 5, which is a modification of my improvement and wherein it is desirable to use the jump-spark ignition system instead of the make and break device described above, I employ means for breaking the primary circuit, as follows: 23 designates an arm that is pivotally secured to the engine cylinder at 24 and is constantly retained against a stop 25 by means of the spring 26. Operatively located with relation to the outer end of the arm 23 is the arm *s* that is mounted on a reciprocating member *t*, the inner end of which arm is adapted to engage a roller 27 that is insulated from the bolt 28 which is mounted in the outer end of the arm 23. A detail view of this structure is shown in Fig. 6. The elliptical end *y* of the member *s* is designed to contact with the roller 27 during its reciprocating movements whereby the primary circuit will be completed when the part *y* engages the part 27, since the roller 27 will turn when engaged by the part *y* and will at the same time rotate the arm 23, the parts *y* and 27 being the make and break terminals. It is not considered necessary to show in the drawings the electrical connections associated with this modification, but it may be stated that the spark-plug 29 is in electrical circuit with the arm 23.

Referring now to the operation of the preferred construction of my improvement: The shaft 4, which is driven from the engine, imparts (as explained above) rotary movements to the elements 13, 5, and 20, which movements are converted into reciprocating movements by the connecting-rod 19, and from this rod to the member *t*. Considering the member as moving downward in the direction of the arrow 30, shown in Fig. 1, the elliptical member *y* will slide on the elliptical member *r*, forcing the arm *q* into the position shown in Fig. 2, to the left, and compressing the coiled spring *p*. After the slide member *t* has moved downward far enough, permitting the elliptical members *r* and *y* to disengage or snap past each other, the stored energy in the spring *p* will exert itself and violently throw the arm *q* toward the right overcoming momentarily the spring *j* and causing the make and break arm *d* to leave the spark-plug *c*, igniting the charge. After the elliptical lugs *r* and *y* have passed each other on one side they will return on the opposite sides on the return stroke of the slide *t*, and will snap past each other at their opposite apices. When on the return downward

stroke the two elliptical elements r and y will repeat the cycle of operations.

If it is desired to reverse the direction of the rotation of the engine, the lever 9 is rotated from the center point of the arch-shaped arm 11, which operation varies the relation or advances or retards the time of ignition. If the lever 9 is moved upward, as shown in Fig. 4, the engine is made to rotate right-handedly or in the advance direction of the boat, or if it is moved downward, the time of ignition of a charge is retarded and the engine made to rotate in the opposite direction, thus moving the boat astern. This advance and retarded ignition is brought about by means of the bearing-block 5 in which is cut a groove 6 of quarter turn which is engaged by the pin 7, whereby when the sleeve 13 is moved by the lever 9, the crank-pin 31 (to which the connecting rod 19 is secured) is moved in the direction of rotation of the shaft 4, or oppositely, so that the timing of the ignition will take place either before or after the engine passes the dead center line.

When the spring-bolt 10 is withdrawn from the toothed arm 11, the electric circuit is broken since the arm 11 is made a part of the circuit and is insulated from the frame in the machine, as indicated at 32; and when the bolt 10 engages the arm 11, the circuit is closed and the engine thereby rendered operative.

What I claim, is:—

1. In combination with an internal combustion engine, a spark-plug, a make and break device engaging the same, a shaft for operating said device, a spring-actuated means for normally retaining the make and break device in contact with the plug, and spring-actuated means for moving said device away from the plug, and temporarily overcoming the action of the first spring-actuated means, said spring-actuated means including a U-shaped member, rigid with the shaft, and springs mounted in the arms of the U-shaped member, and an arm actuated from the engine for actuating the U-shaped member, whereby the make and break device is operated.

2. A sparking device for internal combustion engines, having in combination, a spark-plug, a make and break device engaging the same, a disk member adapted to be rotated from the engine, means for advancing or retarding the disk member with relation to the position of a crank-shaft of the engine,

a cross-head operated from the disk-member, an arm carried by the cross-head, and adapted to actuate the make and break device, said arm being provided with an elliptical-shaped lug portion, and the make and break device being provided with a second arm, the lug portion of the first arm engaging said second arm.

3. A sparking device for internal combustion engines, having in combination, a spark-plug, a make and break device engaging the same, a disk-member adapted to be rotated from the engine, means for advancing or retarding the disk-member with relation to the position of the crank-shaft of the engine, a cross-head operated from the disk-member, an arm carried by the cross-head, a second arm engaging said arm, a U-shaped member rigid with the make and break device, and springs interposed between the second arm and the U-shaped member, whereby the make and break device is cushioned.

4. A sparking device for internal combustion engines, having in combination a finger, a spark-plug engaged by said finger, a shaft for supporting the finger, a U-shaped member rigid with the shaft, an arm rotatably mounted on the U-shaped member and resilient means interposed between the arm and said member, a lug on the outer end of the arm, a cross-head, an arm pivoted thereto and having a lug thereon adapted to engage the lug of the arm, means for reciprocating the cross-head, whereby when the cross-head is actuated the arm will place a tension on one of the springs of the U-shaped member, and upon the disengagement of the arms the stored energy of the spring will actuate the make and break finger, as described.

5. In combination with a make and break-finger a spark-plug, and rotatable shaft of an internal combustion engine, a bearing-block, a sleeve, means for partially rotating the block from the sleeve, a cross-head connection between the finger and bearing-block, an arm thereon, a stop, a spring on the cross-head, for holding the arm thereagainst, a second arm, said arms having inter-engaging elliptical lugs, and resilient means for actuating the make and break finger from the second arm whereby when the bearing-block is actuated the timing of the spark may be changed.

WILLIAM H. SAUNDERS.
